US00D637077S

(12) **United States Design Patent**
Gonzalez et al.

(10) **Patent No.:** US D637,077 S
(45) **Date of Patent:** ** May 3, 2011

(54) **PACKAGE**

(75) Inventors: **Gabriela V. Gonzalez**, Independence, KY (US); **John Carter McFarland**, Cincinnati, OH (US); **Dale Richard Doyle**, Mack, OH (US); **Ryan Lewis Green**, Mt. Washington, OH (US)

(73) Assignee: **The Procter & Gamble Compnay**, Cincinnati, OH (US)

(**) Term: **14 Years**

(21) Appl. No.: **29/341,533**

(22) Filed: **Aug. 7, 2009**

(51) **LOC (9) Cl.** 09-03

(52) **U.S. Cl.** D9/432

(58) **Field of Classification Search** D9/430-433, D9/414, 418, 420-423; D3/272; 206/278, 206/297, 299, 457, 770, 737, 822; 229/100, 229/101, 101.3, 106, 108, 108.1, 116.1, 116.3, 229/116.5, 121, 122, 201, 213, 221, 222, 229/227, 922, 939, 942, 87.08, 101.2, 193, 229/195, 197; D5/7, 11, 12, 14, 16, 19, 20, D5/25, 26, 27, 30, 57, 47, 53, 61-63

(57) **CLAIM**

The ornamental design for a package, as shown and described.

DESCRIPTION

FIG. 1 is a front, top and side isometric view of a package. The dashed line at the top of the package wrapping around the front and side panels of the package showing a linear series of cuts or scores represent claimed parts of the design;

FIG. 2 is a frontal view of the package of FIG. 1;

FIG. 3 is a rear view of the package of FIG. 1;

FIG. 4 is a side view of the package of FIG. 1;

FIG. 5 is a side view of the package of FIG. 1, opposite the side view shown in FIG. 4;

FIG. 6 is a top planar of the package of FIG. 1; and,

FIG. 7 is a bottom planar view of the package of FIG. 1.

The broken lines within the front plane of the package shown in FIGS. 1 and 2 represent unclaimed environmental subject matter.

1 Claim, 4 Drawing Sheets
